[57] CLAIM

The ornamental design for a refrigerator air freshener, as shown.

DESCRIPTION

FIG. 1 is a side elevational view of a refrigerator air freshener showing our new design;

FIG. 2 is an elevational view taken from one end thereof;

FIG. 3 is a top plan view thereof;

FIG. 4 is an elevational view taken from the side opposite that shown in FIG. 1;

FIG. 5 is an elevational view taken from the end opposite that shown in FIG. 2; and

FIG. 6 is a bottom plan view thereof.
